DESIGN FOR A COMBINED MECHANICAL PENCIL AND KNIFE

Jacob M. Weiss, Brooklyn, N. Y.

Application November 15, 1941, Serial No. 104,166

Term of patent 14 years

To all whom it may concern:

Be it known that I, Jacob M. Weiss, a citizen of the United States, residing at 5216 13th Avenue, in the Borough of Brooklyn, county of Kings, city and State of New York, have invented a new, original, and ornamental Design for a Combined Mechanical Pencil and Knife, of which the following is a specification, reference being had to accompanying drawing, forming part thereof.

Figure 1 is an elevational view of a combined mechanical pencil and knife, showing my new design.

Fig. 2 is an elevational view of the eraser and knife portion thereof shown removed from the body of the pencil.

Fig. 3 is a view similar to Fig. 2 but showing the eraser and knife portion rotated on its longitudinal axis through an angle of 90°.

I claim:

The ornamental design for a combined mechanical pencil and knife, substantially as shown and described.

JACOB M. WEISS.
